UNITED STATES PATENT OFFICE.

ERASTUS E. WINKLEY, OF LYNN, MASSACHUSETTS.

CONVEYER-FEEDING MECHANISM.

Specification of Letters Patent.

Patented Apr. 25, 1916.

1,181,091.

Original application filed August 26, 1910, Serial No. 579,110. Divided and this application filed February 5, 1914. Serial No. 816,725.

To all whom it may concern:

Be it known that I, ERASTUS E. WINKLEY, a citizen of the United States, residing at Lynn, in the county of Essex and State of Massachusetts, have invented certain new and useful Improvements in Conveyer-Feeding Mechanism; and I do hereby declare the following to be a full, clear, and exact description of the invention, such as will enable others skilled in the art to which it appertains to make and use the same.

The present invention relates to mechanism for imparting an intermittent feed movement to a conveyer.

The object of the present invention is to provide a simplified mechanism adapted to either rectilinear or rotary movement of a conveyer, by which a step-by-step advance will be insured with a positive locking of the conveyer against backward movement during the pause between the feeding steps.

In accordance with this object an important characteristic of the invention is found in the novel construction and arrangement of the feeding and locking devices whereby they are caused to coöperate in advancing the conveyer step-by-step and in locking it from movement during the period between the feeding steps.

To the accomplishment of this object and such others as may hereinafter appear, as will be readily understood by those skilled in the art, the invention comprises the features and combinations of parts hereinabove described and particularly pointed out in the appended claims.

In the accompanying drawings the essential principles of the invention are shown as applied to the rotary conveyer table, utilized for transferring heels from the source of supply to the cutting mechanism, of the heel shaping machine illustrated and described in my co-pending application Ser. No. 579,110, filed August 26, 1910, from which the present application has been divided.

In the accompanying drawings: Figure 1 is an end elevation of that portion of the frame of the heel shaping machine of my co-pending application which supports the novel conveyer feeding mechanism, together with said mechanism; Fig. 2 is a right side elevation of the parts shown in Fig. 1 with the frame broken away to better disclose the mechanism; Fig. 3 is a plan of the conveyer

feeding mechanism; Fig. 4 is an elevation of the parts shown in Fig. 3; and Fig. 5 is a transverse section on the line 5—5 of Fig. 4, looking in the direction of the arrows.

In the embodiment of the invention illustrated in the drawings the conveyer, for the present purposes, may be represented as a horizontal rotary table 1. The conveyer 1 is mounted on the upper end of a vertical shaft 2 suitably journaled in the main frame 65 F. The lower end of the shaft is seated in a journal 3 in the cross brace F' and a sleeve 4 surrounds the shaft between the conveyer 1 and the journal 3.

An intermittent rotation of the shaft 2 and the conveyer 1 is produced by mechanism comprising a pinion 29 fixed on the lower end of the shaft, Fig. 1, which pinion is engaged alternately by a conveyer locking-rack 3 and a conveyer feeding or actuating rack 31, which are provided, as shown in Fig. 5, with cylindrical surfaces, so that they may be swung into engagement with the pinion across its plane of movement about a horizontal axis lying substantially in the plane of the latter. The rack 30 forms an integral part of an elongated rocking frame comprising a bar 32 and end-members 33 connecting the rack and the bar. These end members are loosely pivoted on a rod 34 which is mounted at its ends in sleeves 35 and 36 carried at the ends of brackets F² and F³ on the frame F of the machine. These sleeves confine the rocking frame against endwise motion but it is free to rock on the rod 34 so as to throw the conveyer locking-rack 30 into and out of engagement with the pinion 29. This rocking movement is produced by mechanism comprising a crank-arm 37 integral with the frame and pivoted by a universal joint 38, see Fig. 1, to the upper end of a rod 39, the lower end of which is pivoted by a universal joint 40, see Fig. 2, to one arm 41 of a bell-crank lever loosely mounted on a shaft 100 42 journaled in the lower part of the frame F of the machine. The bell-crank lever has a second arm 43 carrying a cam-roll 44 which engages a cam 45 on the cam-shaft C, Figs. 1 and 2, journaled in the frame F above the shaft 42.

The conveyer actuating rack 31 is segmental in cross section and is provided with a hub 46 loosely mounted on the rod 34 and free to rock thereon. This hub is also free 110

to slide on the rod, as it is shorter than the rocking frame of which the conveyer locking-rack forms a member. The rocking movements of the actuating-rack are produced by the rocking movements of the rocking frame, since the side faces of the actuating-rack are closely embraced by the locking-rack 30 at one side and the bar 32 at the other side, as shown in Fig. 5. The 10 cam mechanism, heretofore described, operates to rock the frame and thus throw the two racks 30 and 31 alternately into engagement with the pinion 29. After the actuating rack has been so engaged with the 15 pinion, it is moved longitudinally on the rod 34 to rotate the pinion, and thus to rotate the shaft 2 and the conveyer 1. To this end the actuating rack is engaged by a segmental gear 47 carried upon arms 20 48 pivotally mounted on the shaft 42, Figs. 1 and 2. One of these arms carries a cam-roll 49 which engages a cam 50 on the cam-shaft C. This cam acts to swing the segmental gear at the proper time to move the actuating-rack longitudinally and 25 rotate the conveyer 1. After this movement has been completed the cam 45 operates on the crank arm 37 to rock the actuating-rack out of, and the locking-rack into, 30 engagement with the pinion 29, so that the conveyer is firmly locked against accidental rotation between the feeding movements. While the parts are so locked, the actuating-rack is given a reverse longitudinal 35 movement by its cam-mechanism, to bring it into position to again rotate the pinion by a movement in the other direction, and thus the rack-mechanism operates to continuously rotate the conveyer intermittently 40 in the same direction.

The cam-shaft C from which the mechanism heretofore described derives its movement is rotated by mechanism comprising a pulley 52, which is loosely journaled on 45 one end of the shaft 42. To this pulley is fixed a pinion 53 which meshes with a pinion 54, Fig. 1, fixed on one end of the cam-shaft C.

As will be readily apparent to those skilled in the art the invention is not limited in its application to advancing a conveyer in an angular or circular path but may easily be adapted, by the skilled mechanician, to rectilinear movement. Furthermore, while, as hereinbefore stated, the accompanying drawings illustrate the essential principles of the invention, a skilled mechanician may readily make changes in the proportions and relative arrangement of the features and combinations of parts described to adapt the newly discovered mechanism to a particular use without departing from the scope of the invention which is defined in its true breadth in the appended claims. It should be further under-

stood that the invention, while illustrating and describing a particular means, which is convenient and readily controlled for imparting an intermittent feed movement, is comprehensive in this respect, as defined in the appended claims, it being obvious that those skilled in the art may devise various mechanical devices to carry the invention into practical effect.

What is claimed as new, therefore, is:—

1. A movable member and mechanism for imparting an intermittent feed movement thereto comprising laterally projecting peripherally arranged teeth for said member, a pivot rod adjacent said teeth, a feeding device and a locking device both loosely mounted on said pivot rod, mechanism for reversely rocking said devices on said pivot rod to cause them to alternately engage and disengage said teeth, and means for moving said feeding device along said pivot rod while in engagement with said teeth to advance said member and to return it to its initial position after a disengagement while said member is held from movement by said locking device, substantially as described.

2. A movable member and mechanism for imparting an intermittent feed movement thereto comprising a single set of laterally projecting teeth extending adjacent the entire periphery of said member, a feeding device and a locking device for engaging said teeth both rotatably mounted adjacent said member, mechanism for reversely rocking said devices across the plane of travel of said member to cause them to engage and disengage said set of teeth, and means for moving said feeding device in a direction to advance said member while in engagement with said teeth and to return it to its initial position after a disengagement while said member is held from movement by said locking device, substantially as described.

3. A movable member and mechanism for imparting an intermittent feed movement thereto comprising, a pinion mounted on the axis of rotation of said member, a set of feeding and locking devices both rotatably mounted adjacent said member, means for rotating said devices across the plane of travel of said member to bring them into and out of engagement with said pinion, and means for operating said feeding device for rotating the pinion, substantially as described.

4. A movable member and mechanism for imparting an intermittent feed movement thereto comprising, a pinion mounted on the axis of rotation of said member, a locking device for engaging said pinion, a feeding device movable therewith, and a single means for positively actuating said devices to cause them to engage and disengage the

pinion preparatory to rotating said member and then locking said member from movement, substantially as described.

5. A rotatable member and mechanism for imparting an intermittent feed movement thereto comprising a pinion mounted on the axis of rotation of said member, a pivot rod adjacent said pinion, a feeding rack and a locking rack loosely mounted on said pivot rod, mechanism for reversely rocking said racks simultaneously on said pivot rod to cause them to alternately engage and disengage said pinion, and means for moving said feeding rack along said pivot rod while 10 in engagement with the pinion to rotate said member and to return said feeding rack to its initial position after a disengagement while said member is held from movement by said locking rack, substantially as described.

6. A rotatable member and mechanism for imparting an intermittent feed movement thereto comprising a pinion mounted on the axis of rotation of said member, a pivot rod 25 adjacent the pinion, a feeding rack mounted for rotary and longitudinal movement on said rod, a locking rack mounted for rotary movement only on said rod, means to rock said racks to cause them to alternately engage the pinion, and means for imparting a 30 longitudinal movement to said feeding rack when it is in engagement and the locking rack is out of engagement with said pinion to rotate said member, substantially as described.

7. A rotatable member and mechanism for imparting an intermittent feed movement thereto comprising a pinion mounted on the axis of rotation of said member, a pivot rod 40 adjacent the pinion, a rotary and longitudinally movable hub on said rod, a feeding rack segmental in cross-section carried by said hub, a rotary locking rack on said rod constructed and arranged to embrace the 45 side faces of said feeding rack, means to rock said locking rack on said rod whereby said racks are caused to alternately engage said pinion, and means for longitudinally moving said hub when the feeding rack is 50 in engagement and the locking rack is out of

engagement with the pinion to rotate said member, substantially as described.

8. A rotatable member and mechanism for imparting an intermittent movement thereto having a series of circumferentially arranged teeth comprising a rotatable locking rack and a feeding rack embraced thereby so as to rotate therewith, means for rocking said locking rack across the plane of travel of said member into and out of engagement with said teeth whereby the feeding rack is alternately rocked into and out of engagement with said teeth, and means for moving the feeding rack in the plane of travel of said member while in engagement with said teeth and relatively to the locking rack to rotate said member, substantially as described.

9. A movable member and mechanism for imparting an intermittent feed movement thereto comprising, a toothed actuating part 70 connected with said member, a feeding device and a locking device movably mounted adjacent said part, racks on said devices having teeth of the same size for articulation with the teeth of the actuating part, said 75 racks being arranged adjacent one another so that the teeth of one will form a continuation of the teeth of the other, and means for moving said devices to bring the racks into and out of engagement with said part, substantially as described.

10. A movable member and mechanism for imparting an intermittent feed movement thereto comprising, a toothed actuating part 85 connected with said member, a feeding device and a locking device movably mounted adjacent said part, racks on said devices for articulation with the actuating part arranged to have the teeth of one form a continuation of the teeth of the other, 90 means for moving said devices together to bring the racks into and out of engagement with said part, and means for moving said devices relatively to one another to feed said member, substantially as described.
